(57) **CLAIM**

The ornamental design for a laser receiver for surveying, as shown and described.

DESCRIPTION

FIG. 1 is a perspective view from above, front and right, of the laser receiver for surveying according to my novel design;

FIG. 2 is a perspective view from above, rear and left, of the laser receiver for surveying of FIG. 1;

FIG. 3 is a front view of the laser receiver for surveying of FIG. 1;

FIG. 4 is a plane view of the laser receiver for surveying of FIG. 1;

FIG. 5 is a rear view of the laser receiver for surveying of FIG. 1;

FIG. 6 is a bottom view of the laser receiver for surveying of FIG. 1;

FIG. 7 is a left side view of the laser receiver for surveying of FIG. 1; and

FIG. 8 is a right side view of the laser receiver for surveying of FIG. 1.
